DESIGN FOR A TOY TRUNK

Irving Markham, Woodmere, N. Y.

Application November 4, 1943, Serial No. 111,591

Term of patent 14 years

To all whom it may concern:

Be it known that I, Irving Markham, a citizen of the United States, residing at Woodmere, Long Island, county of Queens, State of New York, have invented a new, original, and ornamental Design for a Toy Trunk, of which the following is a specification, reference being had to the accompanying drawing, forming a part thereof.

Fig. 1 is a front elevational view showing my new design, the rear view being similar thereto in all respects;

Fig. 2 is a top view thereof.

I claim:

The ornamental design for a toy trunk, as shown and described.

IRVING MARKHAM.
